UNITED STATES PATENT OFFICE.

ARTHUR L. TURNIPSEED, OF MEMPHIS, TENNESSEE.

OIL-CELLAR.

SPECIFICATION forming part of Letters Patent No. 759,943, dated May 17, 1904.

Application filed August 24, 1903. Serial No. 170,593. (No model.)

To all whom it may concern:

Be it known that I, ARTHUR L. TURNIPSEED, a citizen of the United States, residing at Memphis, Shelby county, State of Tennessee, have 5 invented certain new and useful Improvements in Oil-Cellars, of which the following is a specification.

My invention relates to certain new and useful improvements in oil-cellars for journal-boxes, and has especial reference to a new device for use with the journal-boxes of a locomotive or car or with other boxes subjected to like pressure—*i. e.*, a pressure from one side only.

The object of my invention is to make an 15 oil-cellar which may be easily removed for cleaning or refilling or to allow the journal-boxes to be raised from the journal when same is desired. I accomplish this object by making a cellar which can be removed by drawing 20 it out to one side, as will be more fully hereinafter set forth in the drawings, specification, and claim.

In the drawings, Figure 1 is a side elevation showing a portion of a locomotive-frame with 25 a journal-box and oil-cellar in place. Fig. 2 is a section on the center line of Fig. 1, but with the bolts and adjusting-screw omitted for the sake of clearness. Fig. 3 is a similar section, except that the oil-box is not sectioned 30 and is shown partially removed. Fig. 4 is a sectional elevation on the line IV IV of Fig. 2.

Referring now to the drawings, in which like numerals indicate the same or like parts in all the views, 1 is the engine-frame, having journal-box guides 2 extending downward therefrom. 3 is the journal-box, and 4 a wedge which is set up by the set-screw 5 to tighten the box in place. The oil-cellar 6 is held by

oppositely-disposed pins 7, which project from its opposite sides near the bottom and one 40 end. These pins slide in opposite grooves 8 in the sides 9 of the journal-box, which grooves extend horizontally nearly across the face of the sides 9 and then drop down at an angle toward the front edge of same. 10 is a slot 45 in the oil-cellar, and 11 a similar slot in one side 9 of the journal-box. 12 is a key which is inserted in this slot to hold the parts together when they are in place.

To remove the box, the key 12 is removed 50 and the cellar pulled forward until the pins 7 come to the front of the slot, when they slip down and allow the cellar to be entirely removed. The cellar may be drawn to the position shown and be dropped down and the 55 pocket be examined without entirely removing it.

Having now fully described my invention, what I claim, and desire to secure by Letters Patent of the United States, is—

The combination with a half-bearing having its sides extended downward and provided with opposite grooves extending horizontally almost across, and then dropped downward at an angle to the front of same, an oil-cellar 65 having opposite pins projecting from its sides and adapted to engage the grooved sides of the bearing and a key locking the bearing and cellar together when the latter is in place.

In testimony whereof I have signed my name 70 to this specification in the presence of two subscribing witnesses.

ARTHUR L. TURNIPSEED.
